CLAIM

The ornamental design for a vacuum cleaner accessory holder, as shown and described.

DESCRIPTION

FIG. 1 is a perspective view of a vacuum cleaner accessory holder showing my new design;

FIG. 2 is a front elevational view thereof;

FIG. 3 is a top plan view thereof;

FIG. 4 is a side elevational view thereof;

FIG. 5 is a rear elevational view thereof;

FIG. 6 is a side elevational view thereof of the side opposite to that shown in FIG. 4; and,

FIG. 7 is a bottom plan.

The broken lines showing the environmental structure is for illustrative purposes only and forms no part of the claimed design.
